RADIO TUNING CONTROL

Albert E. Hedger, Buffalo, N. Y.

Application October 21, 1936, Serial No. 106,841

14 Claims. (Cl. 250—20)

This invention relates to a radio tuning control for actuating the tuning condenser of a radio receiving set.

The principal objects of the invention are: A., to simplify the tuning operation by enabling the operator to deal with only one wave band at a time, and, B., to provide a machine in which the "multiple" or "decimal" system is employed so as to enable extreme accuracy of tuning to be obtained, and C., to enable the operator to manually tune the radio set to the approximately correct position and to then cause the tuning to be rendered precisely accurate by providing suitable automatic means to obtain this result. Numerous other objects of the invention and practical solutions thereof are disclosed in detail in the herein patent specification wherein:—

In the accompanying drawings:—

Fig. 1 is a fragmentary perspective showing one form of radio receiving set provided with my improved tuning control.

Fig. 2 is a fragmentary front elevation thereof.

Fig. 3 is a disassembled elevation of the four strips of graduated indicators.

Fig. 4 is a vertical, longitudinal section through the receiving set, taken on line 4—4, Fig. 2.

Fig. 5 is a vertical, longitudinal section through the receiving set, similar to Fig. 4, but showing the parts in a different operative position.

Fig. 6 is a horizontal section through the receiving set, taken on line 6—6, Fig. 4.

Fig. 7 is a fragmentary, vertical, transverse section through the receiving set, taken on line 7—7, Fig. 6.

Fig. 8 is a fragmentary, vertical, transverse section through the receiving set, taken on line 8—8, Fig. 6.

Fig. 9 is a fragmentary, horizontal section through the receiving set, taken on line 9—9, Fig. 8.

Fig. 10 is a fragmentary, vertical, transverse section, showing one of the locating plungers and its associated parts, and taken on line 10—10, Fig. 5.

Similar characters of reference indicate like parts in the several figures of the drawings.

When a radio receiving set is to be tuned so as to properly receive the radio waves being sent out from any certain radio sending station, it is necessary to turn the tuning condenser 20 (Fig. 6) to the proper position. In the present invention this condenser is preferably, though not necessarily, of the "straight line" type, i. e. the change in KC or MC is directly proportional to its movement. The positioning of such a tun-

ing condenser is commonly termed the "tuning" operation, and it is to this tuning operation that the present invention is exclusively devoted.

This tuning condenser 20 has the usual fixed condenser plates 21 and movable plates 22 which latter are all connected to a condenser shaft 23 which is journaled horizontally and transversely of the radio cabinet 24 on bearing standards 25 and 26 suitably secured to the base 29. To said condenser shaft 23 are secured primary and secondary, condenser-actuating, gears 27 and 27a, while upon said condenser shaft are journaled tertiary and quaternary, condenser-actuating gears 27b and 27c.

The primary, condenser-actuating gear 27 is small and is adapted to be actuated by a rack 28 having very sharp gear teeth as shown in Fig. 4. This rack is actuated by a longitudinal movement of a rack lever 30, to the rear end of which it is integrally connected. The secondary, condenser-actuating gear 27a is adapted to be actuated by a secondary rack 28a which is secured to the rear end of a secondary rack lever 30a. It is to be noted that in the particular embodiment of the invention herein disclosed the secondary, condenser-actuating gear 27a has a diameter three times the diameter of the primary gear 27, and that, therefore, the secondary rack lever 30a must move longitudinally rearward three times as far as the primary rack lever 30 to obtain the same amount of rotation of the condenser shaft 23. In other words, there is a one to three ratio between the primary and secondary rack levers 30 and 30a as regards the effect of their longitudinal movement on the rotation of the condenser shaft 23.

Between the secondary and tertiary rack levers 30a and 30b there is a ten to one ratio, and similarly, there is a ten to one ratio between the tertiary and quaternary rack levers 30b and 30c. This result is obtained by suitable gearing, as shown in Figs. 6 and 4 and which is not deemed necessary to be described in detail.

While gears and racks have been illustrated in the present disclosure to transmit power from the rack levers to the condenser 20, it is to be understood that the power may be transmitted through frictional elements unprovided with teeth but only with "rolling circle" frictional faces.

Each of the four rack levers (for instance, the rack lever 30c shown in Figs. 4, 5, 6 and 8) is fulcrumed on a horizontal, transverse, pivot pin 31. The opposite ends of said pivot pin are provided with spacing sleeves 32 so as to laterally

50

55

centralize their companion rack lever in its companion slide tube 33. Said slide tubes 33 are suitably supported on the base 29 on standards 34 and 340. Each slide tube 33 is provided on its opposite lateral sides with longitudinal guide slots 35 which receive the outer ends of their companion pivot pin 31. Thus, each rack lever may be moved lengthwise of its companion slide tube 33 and rocked in any of its longitudinal positions about its fulcrum pivot pin 31 and thus be caused to move its companion rack upwardly into engagement with its companion condenser-actuating gear.

Pivoted at 36 to the front end of each rack lever is a companion, vertical plunger 37. The latter is vertically, slidably arranged in a tubular slide head 38 which is longitudinally and slidably arranged within the bore of its companion slide tube 33. Each plunger 37 is normally maintained in its uppermost position by the weight of its companion rack which causes an upward thrust at the front end of its companion rack lever, and, consequently, of its companion plunger 37. The upper end of each plunger is provided with a suitable operating knob 40, 40a, 40b and 40c so as to permit its companion plunger to be pushed down and then removed longitudinally. Each plunger extends upwardly through a suitable companion slot 41 formed in the radio cabinet 24, the latter covering up all of the operating mechanism except the operating knobs and other similar operating essentials.

Suitably secured to the rear end of each slide head 38 is a flange 43, whose upper end is bent horizontally rearward so as to enable it to be securely fastened to the lower, front end of a companion flexible strip 44, 44a, 44b and 44c. Each strip is constructed of "celluloid" or other transparent, flexible material, and is guided at its rear end between two sheets of felt or similar soft material 45 and 46 so as to enable the strips to be moved up and down the inclined guide 47 without undue abrasion. A suitable curvilinear directing plate 48 is preferably provided so as to cause said strip to feed smoothly into said inclined guide 47.

Thus, as any certain one of the slide heads 38 is moved forwardly or rearwardly, its companion flexible strip is caused to slide up or down in its inclined guide 47.

Each strip is partially exposed behind a rectangular window 50, 50a, 50b and 50c which pierces the inclined front wall 51 of the cabinet 24 and in which is preferably set a small pane of glass 52 inscribed with a straight, horizontal, hair line 53, 53a, 53b and 53c. Each of these strips (see Fig. 3) is provided with four rows of graduated indicators (54, 54a, 54b, 54c and 55, 55a, 55b, 55c and 56, 56a, 56b, 56c and 57, 57a, 57b, 57c). These graduated indicators bear numbers which correspond to the wave length of the four following wave bands:—

550 -1500 kc. (550-200 meters) American broadcast

65 1.50- 4.00 mc. (200-78 meters) Aircraft, police signals, etc.

4.00- 10.00 mc. (78-30 meters) Foreign broadcast

10.00- 23.00 mc. (30-13 meters) Short wave, amateur phone, etc.

70 Each of these strips is adapted to be manually moved lengthwise by its companion operating knob until the companion hair line of its companion glass 52 registers with the specific number 75 desired when tuning in any particular radio send-

ing station. If, for instance, the operator wishes to tune in the American broadcast station corresponding to 1480 kc., he first pushes the first operating knob 40 downward so as to engage the primary rack 28 with the primary condenser-actuating gear 27. He then moves said knob 40 rearwardly until the numeral "1" of the primary, American-broadcast, graduated indicator 54 appears under the hair line 53 of the first window 50, as shown in Fig. 2. This advances the tuning condenser a certain amount. He then successively moves the three other operating knobs 40a, 40b, and 40c until the numerals 4, 8 and 0 appear as shown. Each of these operations advances the tuning condenser a further amount, the operator allowing each operating knob to rise up, and to thereby disengage its companion rack, before commencing to manually actuate the next operating knob. This successive movement of the different operating knobs operates to successively advance the tuning condenser 29 until it is finally brought to a correct position for receiving radio signals from the particular station desired which in this case was assumed to be station 1480 kc. 25

It is to be noted that the ratio between the movement of the first operating knob 40 and the corresponding movement of the tuning condenser 20 is relatively high. In other words, the ratio of the primary condenser actuating means is 30 high and the condenser rotated a considerable amount for a small movement of the primary operating knob 40. The ratios of the succeeding condenser-actuating means are successively lower. In the particular embodiment of the invention 35 here disclosed, the ratio between the primary and secondary condenser-actuating means is three to one. Concomitantly, the physical dimension of a unit distance on the primary, American-broadcast, graduated indicator 54 of the first flexible strip 44 is three times as great as the physical dimension of a unit distance on the secondary, American-broadcast, graduated indicator 54a of the second strip 44a. This means that the corresponding gear ratios are such that the second 45 operating knob 40a must be moved three times as far as the first operating knob 40 to effect the same movement of the tuning condenser 20.

Each of the succeeding operating knobs 40b and 40c and their racks 28b and 28c must be 50 moved ten times as far as its predecessor to obtain a like amount of condenser movement. This means, of course, that the condenser can be very accurately moved to any desired station in a manner similar to that employed in the construction 55 of an ordinary shop micrometer in which a large, coarse movement of the knurled operating sleeve causes an extremely fine and accurate movement of the sliding head of the micrometer.

It is to be noted that the numbers on the first 60 strip 44 do not all go up to 9, this being due to the idiosyncrasies of the various broadcast bands, plus the fact that it is desirable to have the smallest unit dimensions sufficiently large to be easily located on their companion hair lines. In the 65 second strip 44a, however, all of the numbers go up to 9, and hence this may be termed a strip constructed on the decimal system. The numeral 10 has been omitted in each graduated indicator because it might easily cause confusion and because it is unnecessary, being the equivalent of 1 in the next graduated indicator of the same wave band set of graduated indicators. Similarly, the last two strips 44b and 44c are decimal strips and, 70 obviously, the ratios between the condenser-actu- 75

ating means of the second and third and the third and fourth strips are necessarily equal to ten. Because of this fact the last three strips 44a, 44b and 44c are identical in appearance, although 5 different in function.

In an ordinary radio receiving set the "zero" position is at the 550 kc. American-broadcast station, there being no need to move the condenser to the zero kc. position. This is, of course, because there are no stations which send out radio waves of less than 550 kc. In the present system, which is based upon a multiple or pseudo-decimal system, it is desirable that the set be so arranged that it can be indexed, theoretically at least to receive waves of zero kc. This is because of the inherent qualities of a "decimal" system of condenser actuation. Hence, the condenser of the present invention may be said to be at its zero position (similar to the zero of an ordinary radio set) when the tuning control is set for 550 kc. on the American-broadcast band. From this it follows that, when the tuning control disclosed in the present invention is set at zero kc., the condenser position is negative. This characteristic of the present invention is not advanced as a point of superiority of the present invention, as far as the operation thereof is concerned, but merely as a fundamental feature which must be incorporated in such a radio tuning control if the tuning control is to be based on the multiple system and be as simple and rational as that here disclosed.

It is to be understood that the one condenser 20 is used for all four wave bands, although, of course, for each wave band a different electrical circuit is required. Consequently, the tuning of the radio set for any of the other three wave bands is similar to that just described, except that different graduated indicators are required 30 on the four strips for each of the other three wave bands. For instance, if the operator desires to tune the radio receiving set to station 3.125 mc. on the aircraft wave band he first pushes down the first operating knob 40 and pushes the same 40 rearwardly (with said knob remaining depressed) until the numeral 3 appears on the primary, aircraft-band, graduated indicator 55 of the first strip 44 under the hair line 53 of the first window 50. He then releases said first operating knob 40, thereby disengaging the primary rack 28 from the primary, condenser-actuating gear 27. He then seizes the second operating knob 40a and depresses it and pushes it rearwardly (with said knob 40a remaining depressed) until the numeral 55 50 appears on the secondary, aircraft-band, graduated indicator 55a of the second strip 44a under the hair line 53a of the second window 50a. He then releases said second operator knob 40a and successively actuates the third and fourth 60 operating knobs 40b and 40c until the numerals 2 and 5 of the tertiary and quaternary, aircraft-band, indicator strips 55b and 55c appear under the hair lines 53b and 53c.

The operation of tuning in a station on the foreign-broadcast band (4.00-10.00 mc.) or on the short-wave band (10.00-23.00 mc.) is similar to the foregoing except that the digits on the foreign broadcast and the short-wave, graduated indicators are lined up with the hair lines of the 70 windows 50, 50a, 50b and 50c.

While the present invention has shown a different set of graduated indicators for each wave band, it is to be understood that, if the condensers and the electrical units of the set are appropriately designed, only one set of graduated indi-

cators may be used for all the four wave bands. For instance, the graduated indicators 54b, 55b, 56c and 57c may be used, solely for all wave bands, i. e., without any other graduated indicators, to take care of the other three wave bands. 5 In such case, each of the strips 44, 44a, 44b and 44c would contain only the one graduated indicator, and, if desired, these four strips may be constructed identically in form and size. In such case, of course, the gear ratios between each condenser-actuating means would have a ten to one ratio with its adjacent or neighbor condenser-actuating means. It is to be acknowledged that such a refinement of the invention is not easy of accomplishment in that it requires much cut 10 and try work and that it has not been effected in actual practice, but is deemed, nevertheless, to be a logical carrying out of the spirit of the present invention.

To enable the present invention to be tuned 20 to any desired one of the four wave bands, it is necessary to provide a suitable electric circuit for each band, and to control the selectivity of the circuits by a suitable wave switch which operates in the usual and well known manner not deemed 25 necessary to be described here. This switch is actuated by a suitable wave-switch handle 60. The latter has four operative positions corresponding to the four wave bands, and is arranged at the front end of a horizontal, longitudinal 30 wave-switch shaft 61 (see Fig. 4) which is suitably journaled at 62 in the base 29 of the radio receiving set. Secured to an intermediate part of said wave-switch shaft 61 is a pinion 63 which meshes with a horizontal, transverse rack 64 35 (see Figs. 3 and 4) formed integrally in the lower part of a vertical, transverse shutter plate 65. The latter is slidably arranged on the base 29 in suitable slides 66 so as to be able to move horizontally and transversely of said base. Formed 40 in said shutter plate 65 is a rectangular, indicator aperture 67 in which is fitted a window spanned by some such transparent material as "celluloid" or "Cellophane" having four panes each of which has a different color, for instance pane 70 is white, 45 70a is green, 70b is violet, and 70c is red. The colors of these window panes correspond to the colors of the four sets of graduated indicators of the strips 44, 44a, 44b and 44c as indicated. The one or other of these four colored panes is adapted 50 to be registered with the orifice 75 of a wave-band, indicating lens 71 which is set into the inclined front face 51 of the radio receiving cabinet 24 and receives its illumination from a suitable electric lamp bulb 72 secured to a bracket 73 55 mounted on the base 29 of the set. Thus, as the wave switch handle 60 is turned to any one of its four positions, an appropriate color is emanated from the wave-band, indicating lens 71.

Also formed in the shutter plate 65 is a horizontal row of four, narrow, rectangular slits 74, 74a, 74b and 74c. The width of each of these slits is the same as the width of each of the graduated indicators, and the location of each in the shutter plate is such that when any certain one 65 of the colored panes 70, 70a, 70b or 70c of the shutter aperture 67 is in register with the indicating lens 71, said rectangular slits are all in register with the graduated indicators of one particular wave band. For instance, in Fig. 8 the 70 white pane 70 of the rectangular aperture 67 is in register with the orifice 75 of the lens 71, and the slits 74, 74a, 74b and 74c are in register with the American-broadcast, graduated indicators 54, 54a, 54b and 54c. This arrangement acts not 75

only as a telltale to notify the operator as to just what wave band is ready for tuning, but goes further and actually prevents him from seeing any other graduated indicators except those associated with the particular wave band he is dealing with. This result is effected by reason of the fact that the flexible strips 44, 44a, 44b and 44c are adapted to be illuminated through their companion windows 50, 50a, 50b and 50c from companion electric light bulbs 79, 79a, 79b and 79c (see Fig. 9), but the slits 74, 74a, 74b and 74c only allow the light from these four bulbs to pass through the graduated indicators of one single wave band set of graduated indicators at a time. To carry out this scheme consistently, the different wave-band, graduated indicators of the flexible strips 44, 44a, 44b and 44c are differently colored to correspond with the colored panes 70, 70a, 70b and 70c of the indicator aperture 67. Thus, for any certain position of the wave switch handle 60, the same color is emanated from the indicator lens 71 as appears in the windows 50, 50a, 50b and 50c. This renders the receiving set more foolproof in operation because, after it has been used for some time, the operator learns and automatically associates a certain wave band with a certain color which identifies it.

It is highly desirable in an apparatus of this character that each successive step of operations be very accurately performed. It is also highly desirable that no more dependence be placed upon the operator than is absolutely essential. In the present invention provision is made whereby the operator, in carrying out each operative step, is merely required to effect each successive tuning operation with a moderate degree of accuracy, the device itself causing the tuning to be accurate within extremely small limits. This result is obtained not only by the use of the pseudo-decimal system previously described, but, additionally, by a special form of the plungers 37. The intermediate part of each plunger is provided with a laterally extending lug (see Fig. 10) whose upper edge is formed to provide a knife edge 76. This knife edge is adapted to enter into one or other of a plurality of locating notches 77 formed in its companion slide tube 33, said notches being formed in the one (left) face of the slot 78 which extends along the upper longitudinal face of each slide tube 33 to permit of the longitudinal movement of its companion plunger 37. Thus, if the operator fails to properly longitudinally position any certain plunger 37, the upper knife edge 76 thereof will automatically shift said plunger and its companion slide head 38 longitudinally a small but sufficient amount to effect an accurate positioning of said slide head, and, consequently, of the tuning condenser 20 to which it is operatively connected. It is to be understood that this centralizing operation is completely effected by any certain plunger 37 before its companion rack is disengaged from its companion condenser-actuating gear 21, 21a, 21b or 21c. It is also thought to be obvious that a suitable spring may be employed to push each plunger vertically upward if the herein disclosed employment of unbalanced gravitational forces proves too slow or otherwise not entirely satisfactory.

It is desirable that no electric current be sent to the loud speaker of the radio receiving set while the tuning operation is in progress. To attain this result the present invention provides a cutout switch 80 at the lower end of each plunger 37. The four switches at the lower end of the four plungers 37 are in series with each other

and are thus arranged in the electrical system in such manner that, if any one switch is open, no current will flow to the loud speaker. This result is obtained in the usual and well known manner and is thought to warrant no further comment here. 5

It is also deemed desirable to have means provided whereby, when the radio is being tuned, only one rack at a time can be engaged with its companion condenser-actuating gear, and, when the radio is not being tuned, that none of the racks can be engaged with their companion condenser-actuating gears. This result is obtained by the use of a stop bar 81 which is disposed horizontally and transversely of the machine and is transversely slidably in a pair of brackets 82, 83 secured to the base 29. This stop bar is provided on its lower face with a single rectangular notch 84 which is adapted to either register with any desired one of the rack levers 30, 30a, 30b and 30c, or to be moved transversely to the extreme limit of its motion to the right (as in Fig. 1) in which latter case said notch is out of register with all of said rack levers. 15

The lateral shifting of said stop bar is effected manually by a safety knob 85 which is preferably pointed at its rear end, as shown, to enable its position to be accurately gauged. Said safety knob is secured to the upper end of a safety post 86 which extends through a horizontal, transverse slot 87 formed in the cabinet 24 of the radio receiving set to permit transverse movement of said safety post. The lower end of said safety post 86 is secured to a horizontal, transverse slide rod 88 which is slidably mounted on the base 29 in a slide tube 90 which is secured at its opposite ends to the base 29 in brackets 91, 92, said slide tube 90 being slotted on its upper face at 93 to permit the safety post 86 to move horizontally and transversely of the radio set, 40 together with the slide rod 88 to which it is connected. The opposite ends of said slide rod 88 are bent horizontally rearward, as shown in Fig. 6, and are suitably secured at their rear ends to the opposite ends of the stop bar 81. 45

Said pointed safety knob 85 is in the same vertical, longitudinal plane as the notch 84 of the stop bar 81 so that the operator can easily tell by the position of said knob what the position of said notch is. This alignment operation is facilitated by the position of the four horizontal, longitudinal slots 41 which pierce the radio cabinet to permit longitudinal movement of the plungers 37. 50

Operation

We will first assume that the operator wishes to tune in the radio receiving set to station 1480 kc. on the American-broadcast radio band. He first turns the wave switch handle 60 until a white light flashes through wave-band indicating lens 71. This operation simultaneously brings the four rectangular slits 74, 74a, 74b and 74c of the shutter plate 65 into register with the American-broadcast, graduated indicators 54, 54a, 54b and 54c, and thereby causes the latter to be illuminated from their companion lights 79, 79a, 79b and 79c with a white color inasmuch as the color of these particular graduated indicators is white. All of the other graduated indicators are at this time totally invisible because they are so constructed as to only be visible when light is reflected from their front surfaces. 65

The operator now moves the safety knob 85 laterally until it registers with the slot 41 of the 70

primary operating knob 40. This causes the notch 84 of the stop bar 81 to register with the primary rack lever 30 and permits the rear end of the latter to be elevated. The operator now 5 grasps the primary operating knob 40 and pushes it downwardly. This opens its companion cut-out switch 80 and thereby disconnects the loud speaker while this particular tuning operation is in progress. This movement also lifts the rear 10 end of the primary rack lever 30 so as to cause the sharp pointed teeth of the rack 28 thereof to mesh with the sharp pointed teeth of the primary condenser-actuating gear 27. The operator now (with said operating knob 40 still depressed) moves said primary operating knob 15 rearwardly until the numeral 1 of the primary, American-broadcast, graduated indicator 54 registers with the hair line 53 of window 50. This causes the tuning condenser 20 to be rotated an 20 amount corresponding to the movement of said primary operating knob 40. The operator now releases said primary operating knob 40, and thereby allows its knife edge 76 to accurately engage with the adjacent locating notch 77 of 25 its companion slide tube 33. This causes the tuning condenser to be very accurately located, as far as this initial tuning step is concerned, even though the operator does not move the primary operating knob to precisely the position intended, said knife edge 76 causing a slight longitudinal shifting of its companion rack lever in the event that the latter has been longitudinally positioned in an approximately correct but not an exactly correct position.

30 The operator now shifts the safety knob 85 to the right so as to position the same in register with the secondary operating knob 40a. He then pushes the latter down and moves it rearwardly until the numeral 4 of the secondary, American-broadcast, graduated indicator 54a is in line with the hair line 53a. This process is carried out in a similar fashion so as to position the numerals 8 and 0 of the tertiary and quaternary, American-broadcast, graduated indicators 54b and 54c under the hair lines 53b and 53c. If the operator desires 35 that this tuning position be not accidentally altered, he moves the safety knob 85 to its extreme right position, as shown in Fig. 1, thereby preventing any manipulation of any of the operating knobs 40, 40a, 40b or 40c.

The operator now regulates the volume control switch 94 and the sensitivity switch 95 in the usual and well known manner.

We will now assume that the operator wishes to 40 tune in station 3.125 mc. on the aircraft-wave band. He first turns the wave-switch handle 60 until a green light is seen through the wave-band, indicating lens 71. This operation simultaneously illuminates all of the aircraft-band, 45 graduated indicators 55, 55a, 55b and 55c which are colored green to match the light coming through the indicating lens 71. The rest of the graduated indicators are at this time invisible. The operator now moves the safety knob 85 over to its extreme left position in line with the slot 41 of the primary operating knob 40. He then pushes down the latter and moves it longitudinally until the numeral 3 of the primary, aircraft-band, graduated indicator 55 is under the hair line 53 of the first window 50. He then releases said primary operating knob 40 and moves the safety knob 85 to the right into register with the slot 41 of the secondary operating knob 40a. He then depresses the latter and moves it longitudinally until the numeral 1 of the secondary, aircraft-

band, graduated indicator 55a registers with the hair line 53a of window 50a. He then, in a similar manner, locates the numeral 2 of the tertiary, aircraft-band, graduated indicator 55b under hair line 53b, of window 50b and thereafter locates 5 the numeral 5 of the quaternary, aircraft-band, graduated indicator 55c under hair line 53c of window 50c.

It is to be noted that when the operator shifted from station 1480 kc. on the American-broadcast band to station 3.125 mc. on the aircraft-band, he did not have to return the radio receiving set to its zero position, but merely shifted each of the operating knobs in turn to its new position. This operation, incidently, he can effect by moving 15 said operating knobs in any order he may desire.

I claim as my invention:

1. A radio tuning control associated with the tuning condenser of a radio receiving set and comprising: a pair of graduated indicators having 20 their graduations of different length and normally disconnected from the condenser; and a pair of condenser actuating means of different transmitting ratio, each of said means being adapted to connect its companion indicator with 25 the condenser.

2. A radio tuning control associated with the tuning condenser of a radio receiving set and comprising: a pair of graduated indicators having 30 their graduations of different length and normally disconnected from the condenser; and a pair of condenser actuating means of different transmitting ratio, each of said means being adapted to connect its companion indicator with the condenser, the arrangement being such that when 35 the indicators are both set at zero the condenser is in a negative position.

3. A radio tuning control associated with the tuning condenser of a radio receiving set and comprising: a pair of graduated indicators having 40 their graduations of different length and normally disconnected from the condenser; and a pair of condenser actuating means of different transmitting ratio, each of said means being adapted to connect its companion indicator with the condenser, the arrangement being such that when 45 the indicators are both set at zero the condenser is in a negative position and, when the indicators are set for the lowest station in any certain wave band, the condenser is in its zero position.

4. A radio tuning control associated with the tuning condenser of a radio receiving set and comprising: a pair of indicators normally disconnected from the condenser, each indicator having a plurality of graduations and the corresponding 55 graduations of the indicators relatively to each other having the same ratio; and a pair of condenser actuating means of different ratio, each of said means being adapted to connect its companion indicator with the condenser.

5. A radio tuning control associated with the tuning condenser of a radio receiving set and comprising: a pair of indicators normally disconnected from the condenser, each indicator having a plurality of graduations and the corresponding 65 graduations of the indicators relatively to each other having the same ratio; a pair of condenser actuating means of different ratio, each of said means being adapted to connect its companion indicator with the condenser; and means for illuminating the one or other set of graduations 70 on the indicators.

6. A radio tuning control associated with the tuning condenser of a radio receiving set and comprising: a pair of indicators normally dis- 75

connected from the condenser, each indicator having a plurality of graduations and the corresponding graduations of the indicators relatively to each other having the same ratio; a pair of condenser actuating means of different ratio, each of said means being adapted to connect its companion indicator with the condenser; and means for illuminating the one or other set of graduations on the indicators consisting of a plate having a pair of apertures and adapted to be moved so as to have said apertures register with the one or other set of graduations.

7. A radio tuning control associated with the tuning condenser of a radio receiving set and comprising: a pair of indicators normally disconnected from the condenser, each indicator having a plurality of graduations and the corresponding graduations of the indicators relatively to each other having the same ratio; a pair of condenser actuating means of different ratio, each of said means being adapted to connect its companion indicator with the condenser; a wave switch; and means for co-relating the position of said switch with one or other set of graduations on the indicators.

8. A radio tuning control associated with the tuning condenser of a radio receiving set and comprising: a pair of indicators normally disconnected from the condenser, each indicator having a plurality of graduations and the corresponding graduations of the indicators relatively to each other having the same ratio; a pair of condenser actuating means of different ratio, each of said means being adapted to connect its companion indicator with the condenser; a wave switch; and a wave light, the color of the illumination from which is controlled by said wave switch and is co-related with the sets of graduations on the indicators.

40 9. A radio tuning control associated with the tuning condenser of a radio receiving set and comprising: a pair of indicators normally disconnected from the condenser, each indicator having a plurality of graduations and the corresponding graduations of the indicators relatively to each other having the same ratio; a pair of condenser actuating means of different ratio, each of said means being adapted to connect its companion indicator with the condenser; a wave switch; a wave light; and means for illuminating the one or other set of graduations on the indicators and simultaneously controlling the color of the illumination emanating from said wave light, consisting of a plate adapted to be moved by said wave switch and having a pair of apertures adapted to register with the one or other set of graduations and having a pair of colored members, the one or other of which is adapted to register with the wave light.

60 10. A radio tuning control associated with the tuning condenser of a radio receiving set and comprising: a pair of graduated indicators hav-

ing their graduations of different length and normally disconnected from the condenser; a pair of condenser actuating means of different transmitting ratio, each of said means being adapted to connect its companion indicator with the condenser; and means for shifting each condenser actuating means to one or other exact location when said actuating means is shifted to approximately the correct position.

11. A radio tuning control associated with the tuning condenser of a radio receiving set and comprising: a pair of graduated indicators having their graduations of different length and normally disconnected from the condenser; a pair of condenser actuating means of different transmitting ratio, each of said means being adapted to connect its companion indicator with the condenser; a precision member having a plurality of V-shaped notches corresponding with the graduations of said indicators; and a pointed plunger adapted to engage with the one or other of said notches and to be longitudinally movably connected with one of said condenser actuating means.

12. A radio tuning control associated with the tuning condenser of a radio receiving set and comprising: a pair of graduated indicators having their graduations of different length and normally disconnected from the condenser; a pair of condenser actuating means of different transmitting ratio, each of said means being adapted to connect its companion indicator with the condenser; and means for preventing more than one of said condenser actuating means being actuated at a time.

13. A radio tuning control associated with the tuning condenser of a radio receiving set and comprising: a pair of graduated indicators having their graduations of different length and normally disconnected from the condenser; a pair of condenser actuating means of different transmitting ratio, each of said means being adapted to connect its companion indicator with the condenser; and means for preventing more than one of said condenser actuating means being actuated at a time and for preventing all of said actuating means being actuated when the radio tuning operation has been completed.

14. A radio tuning control associated with the tuning condenser of a radio receiving set and comprising: a pair of graduated indicators having their graduations of different length and normally disconnected from the condenser; a pair of condenser actuating means of different transmitting ratio, each of said means being adapted to connect its companion indicator with the condenser; and a cutout switch in series with the electrical system of the radio set and adapted to be opened whenever any one of the condenser actuating means is being actuated.

ALBERT E. HEDGER.
